UNITED STATES PATENT OFFICE.

ANTOINE VAN DEN PLAS, OF BRUSSELS-CINQUANTENAIRE, BELGIUM.

DESIGN FOR A MUD-GUARD.

45,773.

Specification for Design.

Patented May 12, 1914.

Application filed September 16, 1912. Serial No. 720,693. Term of patent 7 years.

To all whom it may concern:

Be it known that I, ANTOINE VAN DEN PLAS, a subject of the King of Belgium, residing at Brussels - Cinquantenaire, Belgium, have invented a new, original, and ornamental Design for Mud-Guards, of which the following is a specification, reference being had to the accompanying drawing, forming part thereof, in which—

Figure 1 is a side elevation of the guard viewed slightly from below and showing my new design. Fig. 2 is a top plan view thereof. Fig. 3 is a three quarter perspective

view of the guard seen from the front on the side turned toward the chassis, showing the new design. Fig. 4 is a similar view of the highly embellished mud-guard.

I claim:

The ornamental design for a mud-guard, as shown.

In testimony whereof I affix my signature in presence of two witnesses.

ANTOINE VAN DEN PLAS.

Witnesses:

GASTON MAEZ,
CHAS. ROY NASMITH.
